AUTOMOBILE BRUSH SPRAY

Lester G. Casterline, Flushing, N. Y.

Application May 16, 1934, Serial No. 725,965

4 Claims. (Cl. 15—128)

This invention relates to new and useful improvements in an automobile brush spray.

The invention has for an object the construction of a device as mentioned which is characterized by an arrangement whereby a hollow brush base of metal is associated with bristles in a novel fashion for the construction of a brush. A feature of the arrangement is the lack of wooden parts.

10 Still further the invention particularly proposes an arrangement wherein the hollow brush base is provided with a plurality of openings for the passage of liquid among the bristles for better aid in cleaning with the brush.

15 Still further the invention also proposes an arrangement wherein the hollow brush base is associated with a hollow handle and a pipe line for a supply of cleaning fluid.

Another one of the objects of this invention is 20 the arrangement of a plurality of groups of bristles mounted upon said brush base and including threaded studs threadedly engaging into the brush base whereby they may be removed and replaced when desired.

25 Still further the invention also proposes the provision of a valve adapted to control the supply of liquid within the hollow brush base and so control the supply of liquid to the bristles.

Another one of the objects of this invention is 30 to so arrange the brush base that it is convenient for cleaning various parts of a vehicle for example, the spokes of the wheels, or of a different shape for cleaning the windows.

Still further the invention also proposes an 35 arrangement wherein the hollow brush base is arranged with openings for supplying water to the bristles, with these openings arranged in specific relation so as to be directed away from the user so that the possibility of spraying the user 40 with water is eliminated.

Still further the invention proposes an arrangement whereby four resilient strips are associated with certain of the groups of the bristles and are adapted to engage over and cover certain 45 of the openings for the purpose of selectively controlling the direction of discharge of the liquid.

Still further the invention proposes the construction of a device as mentioned which is simple and durable and which may be manufactured and sold at a reasonable cost.

50 For further comprehension of the invention, and of the objects and advantages thereof, reference will be had to the following description and accompanying drawing, and to the appended

claims in which the various novel features of the invention are more particularly set forth.

In the accompanying drawing forming a material part of this invention:

Fig. 1 is a side elevational view of a device constructed according to this invention.

Fig. 2 is a transverse sectional view taken on the line 2—2 of Fig. 1.

Fig. 3 is a fragmentary side elevational view looking from the right hand side of Fig. 2.

Fig. 4 is a fragmentary sectional view taken on the line 4—4 of Fig. 3.

Fig. 5 is a fragmentary sectional view taken on the line 5—5 of Fig. 4.

Fig. 6 is a fragmentary sectional view taken on the line 6—6 of Fig. 3.

Fig. 7 is a fragmentary sectional view taken on the line 7—7 of Fig. 6.

Fig. 8 is a fragmentary enlarged sectional view taken on the line 8—8 of Fig. 1.

Fig. 9 is a sectional view taken on the line 9—9 of Fig. 8.

Fig. 10 is a side elevational view of another brush spray constructed according to another embodiment of this invention.

Fig. 11 is a fragmentary elevational view looking in the direction of the line 11—11 of Fig. 10.

The automobile brush spray according to this invention includes a hollow brush base 10 connected with a hollow handle 11 and with a pipe line 12 for the supply of water. The free end of the pipe line is provided with a coupling 13 by which it may be attached to a faucet of a water supply. The other end of the hose 12 is connected with a standard fitting 14 upon the outer end of the handle 11 by which it may be connected and disconnected from the handle, said fitting being a conventional coupling. The interior of the handle 11 is hollow, see Fig. 8, and the brush base 10 extends into the front end of said hollow. The brush base 10 is of hollow construction closed at the outer end 15. A plurality of groups of bristles 16 are mounted upon the brush base and include threaded stud portions 17 threadedly engaging into the brush base. Said hollow brush base 10 is formed with a plurality of small openings 18 arranged among the bristles for the purpose of supplying water to the groups of bristles.

A valve controls the supply of water to the interior of the brush base. This valve comprises a conventional rotary valve 20 of tapered shape and is located in a peculiar position so as to simultaneously function also to hold the brush base connected with the handle. More particularly the valve 20 engages transversely through the end 55

of the handle and through the end of the brush base 20. This tapered valve is formed with a passage 21 which when located at right angles to the passage of the brush base closes the passage but when in line allows the passage of water. The upper end of the valve 20 is provided with a handle 22 by which it may be turned. The lower end is equipped with a washer 23 held in position with a screw 24 which prevents the valve 20 from moving from its position.

Each group of bristles comprises a small cup 25 having a plurality of cuts 26 extended in from the edge so as to give it resiliency. The bristles 16 are engaged at one of their ends into the cup 25 and tightly clamped in position and so maintain their place. The bottom end of each of the cups 25 is formed with a threaded stud 17 for engaging into a receiving opening into the brush base.

20 A plurality of resilient straps 27 are associated with certain of the groups of bristles and are clamped in position upon the brush base by the threaded studs of the groups and are provided with valve members 28 adapted to engage in certain of the openings 18 for the purpose of closing these openings. The arrangement is such that the hollow brush base may be held in any inoperative position and openings 18 which are directed to spray water towards a user may thus 25 be closed to eliminate this inconvenience. More particularly each of the resilient strips 27 is formed intermediately with a bent portion, see Fig. 6, so as to normally tend to move the outer free ends downwards and so tightly close the valve members 28 upon the openings. The clamped ends of each of the strips 27 are formed with slots 29 extended in from the free end which arrangement allows removal of the strips by slightly turning the cup 25 to release the clamping action between the cups and the ends of the strip. This 30 arrangement permits complete removal of any of the resilient strips and replacement in any other position.

Furthermore the arrangement allows the resilient strips 27 to be turned and clamped into a new position, as for example indicated by the dot and dash lines 27' in Fig. 3 for the purposes of being in idle positions. In these idle positions none of the openings 18 are restricted. With this 35 arrangement, all, or any number of the openings 18 may be closed when desired.

In Figs. 10 and 11 another embodiment of the invention has been disclosed wherein an automobile brush spray is shown adapted particularly 40 for the cleaning of the windows of a car. This brush spray includes a cup shaped member 30 formed with a closed end 31 provided with a plurality of openings 32 for the passage of the water and with a plurality of groups of bristles 16 as 45 previously described. Certain of the openings 32 may be closed by the provision of the resilient strips 27 arranged to be clamped down by the studs of the cup shaped members of the bristles. These strips 27 are provided with valve members 60 50 65 20 as previously described. The cup shaped member 30 is connected with a hollow handle 33 by which it may be readily manipulated. The end of the handle is provided with a coupling 34 connected with a flexible hose 35 to a supply of 70 water.

While I have shown and described the preferred embodiments of my invention, it is to be understood that I do not limit myself to the precise constructions herein disclosed and the right is reserved to all changes and modifications coming within the scope of the invention as defined in the appended claims. 5

Having thus described my invention, what I claim as new, and desire to secure by United States Letters Patent is:— 10

1. In an auto brush spray, a hollow cylindrical brush base of metal connected with a hollow handle and a pipe line for a supply of water, a plurality of groups of bristles mounted upon said brush base and including threaded studs threadedly engaging into said base, and said hollow brush base being formed with a plurality of small openings on various sides for the passage of water among said groups of bristles, and means supported on said studs for closing contiguous small 20 openings to prevent the passage of liquid from the hollow brush base in a certain direction.

2. In an auto brush spray, a hollow cylindrical brush base of metal connected with a hollow handle and a pipe line for a supply of water, a 25 plurality of groups of bristles mounted upon said brush base and including threaded studs threadedly engaging into said base, said hollow brush base being formed with a plurality of small openings on various sides for the passage of water 30 among said groups of bristles, and resilient strips clamped upon said brush base by said threaded studs and carrying valve members engaging contiguous openings for closing the openings.

3. In an auto brush spray, a hollow cylindrical 35 brush base of metal connected with a hollow handle and a pipe line for a supply of water, a plurality of groups of bristles mounted upon said brush base and including threaded studs threadedly engaging into said base, said hollow brush 40 base being formed with a plurality of small openings on various sides for the passage of water among said groups of bristles, and resilient strips clamped upon said brush base by said threaded 45 studs and carrying valve members engaging contiguous openings for closing the openings, the clamped ends of said resilient strips being formed with slots engaged from the free ends whereby said strips are removable upon slight loosening of the clamping action. 50

4. In an auto brush spray, a hollow cylindrical brush base of metal connected with a hollow handle and a pipe line for a supply of water, a plurality of groups of bristles mounted upon said brush base and including threaded studs threadedly 55 engaging into said base, said hollow brush base being formed with a plurality of small openings on various sides for the passage of water among said groups of bristles, and resilient strips clamped upon said brush base by said threaded 60 studs and carrying valve members engaging contiguous openings for closing the openings, the clamped ends of said resilient strips being formed with slots engaged from the free ends whereby said strips are removable upon slight loosening 65 of the clamping action, and said resilient strips being adapted to be placed into inoperative positions and clamped in these positions with said threaded studs.

LESTER G. CASTERLINE. 70
